DESIGN FOR A BUILDING

William C. Pahlmann and Caleb Hornbostel,
New York, N. Y.

Application October 2 1940, Serial No. 95,565

Term of patent 3½ years

To all whom it may concern:

Be it known that we, William C. Pahlmann and Caleb Hornbostel, citizens of the United States of America, residing in New York city, in the county of New York and State of New York, have invented a new, original, and ornamental Design for a Building, of which the following is a specification, reference being had to the accompanying drawings, forming part thereof, wherein,

We claim:

The ornamental design for a building, substantially as shown.

WILLIAM C. PAHLMANN.
CALEB HORNBOSTEL.
